UNITED STATES PATENT OFFICE.

ROBERT SCHEY, OF NEW YORK, N. Y.

FABRIC SAMPLE OR SWATCH.

1,214,832.

Specification of Letters Patent. Patented Feb. 6, 1917.

Application filed February 20, 1914. Serial No. 819,893.

To all whom it may concern:

Be it known that I, ROBERT SCHEY, a citizen of the United States, and resident of the borough of Manhattan, city, county, and State of New York, have invented certain new and useful Improvements in Fabric Samples or Swatches, of which the following is a specification.

My invention relates to improvements in samples or swatches of fabric for displaying material adapted more particularly for use in making dresses or other articles of wearing apparel, and has for its object to provide a sample of such fabric upon which a 10 production of a dress or other article of wearing apparel is printed or otherwise produced in outline, in black or in colors, for the purpose of indicating to a prospective purchaser how the particular material will look 15 when made up as a dress or other article of wearing apparel.

Other objects of my invention will appear from the description hereinafter and the features of novelty will be pointed out in 20 the appended claim.

Reference is to be had to the accompanying drawing in which Figure 1 illustrates a face view of a sample or swatch of undyed material including my improvement, and 25 Fig. 2 is a similar view of a sample of the same material after it has been dyed.

As illustrated, the drawings represent a sample or swatch of fabric 1 of a certain texture or weave before the said fabric has 30 been dyed or otherwise colored. Upon this sample of undyed fabric or material is produced an outline 2 of a dress or other article of wearing apparel either represented upon a human figure as illustrated or otherwise 35 as may be desired, the said outline being printed or otherwise produced upon the fabric preferably so as to appear only upon one surface thereof. The sample 1 may show 40 this outline alone to indicate how the dress or the like will appear when made of said material before it is dyed, or in other words 45 in white. In order to show how the partic-

ular material will look when made of the same material after it has been dyed or printed, I accompany the above sample 1 with an additional sample 3 of the same fabric shown in Fig. 2 and dyed in any color and in this case as indicated at 4 fill in the said outline on the sample 1 in a color to correspond with the dyed sample 3. In 50 other words if the outline is filled in in blue a sample 3 of the same material dyed blue will accompany the sample 1 or if filled in in brown, a brown sample 3 will accompany the same and so on, the color filled in in the 55 outline in each case corresponding with the color of the dyed sample 3. It will of course be understood that a number of undyed samples of material either showing the outline alone or each showing an outline filled in 60 in a different color and accompanied by samples of correspondingly dyed material may be provided. Thus if the prospective purchaser decides upon a white garment or the 65 like all that is necessary in order to obtain 70 an idea of how such garment will look, is to turn to the sample of undyed fabric showing the mere outline thereof. Similarly if the purchaser decides upon a blue fabric it is only necessary to turn to the undyed sample 75 containing an outline filled in in blue in order to definitely ascertain just how this blue fabric will look when made up. It will readily be seen that the same is true of any 80 of the other colors which may be displayed in the collection of samples. My improvement thus provides a sample illustrating the appearance of the weave or texture of the fabric before being dyed and also showing 85 how a garment made up of such material when dyed a particular color will look and at the same time provides a sample of the goods actually dyed to show for instance how said material takes the dye and its 90 actual appearance after being dyed.

In some cases the outline of the garment or the like may be produced on a sample of dyed fabric, and in other cases this outline when so produced on a sample of dyed fab-

ric may be filled in with different shades of the color in which the said sample is dyed or in contrasting colors.

Various changes in the form shown and 5 described may be made within the scope of the claim without departing from the spirit of my invention.

I claim:

10 A sample of the kind described comprising a specimen of undyed fabric, and a representation of a garment or the like pro-

duced in color only upon one surface thereof so as to cover only a portion of said surface.

15 In testimony whereof, I have hereunto set my hand in the presence of two subscribing witnesses.

ROBERT SCHEY.

Witnesses:

JOHN A. KEHLENBECK,
FRITZ ZIEGLER, JR.
